UNITED STATES PATENT OFFICE.

BIRNEY C. BATCHELLER, OF PHILADELPHIA, PENNSYLVANIA, ASSIGNOR TO THE PEARSALL PNEUMATIC TUBE AND POWER COMPANY, OF NEW YORK, N. Y., A CORPORATION OF NEW YORK.

PNEUMATIC-DESPATCH-TUBE APPARATUS.

1,115,770.

Specification of Letters Patent.

Patented Nov. 3, 1914.

Application filed March 11, 1905, Serial No. 249,569. Renewed February 6, 1913. Serial No. 746,671.

To all whom it may concern:

Be it known that I, BIRNEY C. BATCHELLER, a citizen of the United States of America, residing in the city and county of Philadelphia, in the State of Pennsylvania, have invented a certain new and useful Improvement 5 in Pneumatic-Despatch-Tube Apparatus, of which the following is a true and exact description, reference being had to the accompanying drawings, which form a part thereof.

My invention relates to pneumatic despatch-tube apparatus of the kind in which a vacuum is employed and it has for its object 15 to provide improved means for opening and closing the transit tube to the vacuum pipe or reservoir.

The nature of my improvements will be best understood as described in connection 20 with the drawings in which they are illustrated and in which—

Figure 1, is an elevation representing two stations connected by a transit tube and equipped with my improved mechanism. 25 Fig. 2, is a plan view of the station mechanism embodying my improvements. Fig. 2^a is a partial sectional elevation on the line a—a of Fig. 2. Fig. 3, a vertical section on the line 3—3 of Fig. 2. Fig. 4, a vertical section on the line 4—4, of Fig. 2. Fig. 5, 30 a plan of the station device viewed from the bottom, and Figs. 6 and 7, diagrammatic views illustrating the nature and operation of my improved device.

35 A, is the transit tube which in the plan shown is a single tube having open ends A', A', in two connected stations, B, B, etc., indicating curved receivers by which the carrier is engaged when it leaves the 40 transit tube.

C, C, indicate the vacuum pipe or pipes in which a constant vacuum is maintained by mechanism not shown.

D, D, etc., are the station appliances 45 which, as shown, consist of a chamber D', in permanent connection with the pipe C, and connected through a cylindrical passage D⁸, with the chamber D², which chamber connects with the atmosphere through a second cylindrical passage D⁴, and by means 50 of a lateral passage D⁵, with openings D⁷, in the transit pipe. The lateral passage D⁵, as shown, extends around a vertical passage D⁶, which is provided for the passage of

a rod M, the purpose of which will be here- 55 after described.

In the construction shown the casting forming the chamber D², is connected by integral webs D⁸, D⁸, with a cylinder indicated at D⁹, which cylinder is open at the top and 60 through a passage D¹⁰, connected with the pipe J², by which the cylinder can be placed in communication with the vacuum pipe, a lateral port D¹¹, D¹², having in it a valve seat D¹³, which connects cylinder D⁹, with 65 the atmosphere.

E, is an adjustable abutment screw extending into the bottom of the cylinder D⁹.

F, is a cylindrical valve moving in the cylindrical chamber D⁸, and connected with 70 a cylindrical valve F', which is adapted to move in the cylindrical chamber D⁴. This double valve, by means of the spindle F², is connected with the piston F³, of the cylinder D⁹. 75

F⁴ is a shoulder secured on the spindle F², as indicated in Figs. 3 and 4.

G, is a shaft extending between two of the webs D⁸, and serving to pivotally support the lever G', having the laterally extending lever arm G², which is drawn downward by the action of a spring G³. 80

H, see Fig. 3, is a valve adapted to seat itself on the port D¹³, and provided with a valve spindle H', having a split ring H², secured 85 near its upper end which upper end extends through a hole in the lever G². The valve is normally seated by the action of a spring H³.

I, is a three way valve or cock casing in 90 which works the three way valve I', see Figs. 6 and 7. The valve casing has one of its ports connected by a pipe J, with a vacuum pipe C, another connected by the pipe J', with the similar port of a valve casing 95 in the connected station, and a third connected by pipe J², with the cylinder D⁹.

K, see Figs. 3 and 4, is the spindle of the valve I', supported in convenient bearings and turned by means of a handle K'. Secured on the spindle K, is a collar K², having a projecting finger K³, see Figs. 2 and 3, which extends under and normally lies close against a valve L, which valve normally closes the end of the tube A and is hinged 100 on the spindle K, by hinge lugs L', L'. A spring L², acts to hold the valve L, closed. 105

L⁴, indicates a lug or lugs on the valve L,

to which is connected a rod M, best shown in Fig. 3, the lower end of the rod extending through a perforation in the lever arm G², and having an enlargement M', secured 5 on it in proper position to engage the said lever arm for purposes to be described.

N, Fig. 7, indicates a carrier in process of transmission through the tube.

In the diagrammatic Figs. 6 and 7, I have 10 indicated the parts shown in Figs. 1 to 5 inclusive in simplified form, but use the same indicating letters, marking for instance the upper face of the disk valve secured to the stem F², with the symbol F', 15 and the lower face with the symbol F; this disk valve being substantially the same in its connections and operation as the two piston valves F and F'.

The valves and valve actuating appliances 20 are normally in the position shown in Figs. 3, 4 and 6, that is to say, the valves I' are turned so as to connect the two cylinders D⁹, D⁹, through the pipe J', J', and cut both of them off from the pipes J, which pipes 25 connect with the vacuum tube C. The valves L, L, are also closed and the tube A, is in free communication with the atmosphere at both ends. When it is desired to send a carrier from, for instance, the right hand station to the left hand station of the diagrammatic figures, the operator turns the valve I', at the right hand station to the position shown in Fig. 7, thereby connecting the cylinder at the left hand station through the 30 pipe J', with the pipe J, and vacuum pipe C, at the right hand station. This connection causes the piston F³, to move in a direction to actuate the valve F, F', to open the left hand end of the transit tube to the 35 vacuum tube C, and cut off its connection with the atmosphere; the right hand end of the transit tube being still in connection with the atmosphere the air flows in at the right hand end and the carrier moves rapidly to the left hand end of the tube, finally 40 lifting the valve L, and issuing therefrom.

To refer more particularly to the detail mechanism shown in Figs. 2 to 5, it will be seen that when the cylinder D⁹, is connected 50 to the vacuum pipe, as described, the piston F³, will be drawn down, as will also the piston valves F, and F', the valve F', entering the cylindrical passage D⁴, and cutting off atmospheric connection with the chamber D², just as the piston valve F, passes out of the cylindrical chamber D³, and admits the vacuum from the pipe C, into the chamber D². When the stroke of the piston F³, and its connected parts is completed the 55 spring G³, acting on the lever arm G², causes the lever arm G², to engage with the shoulder F⁴, thereby locking the air valve F, F', in open position, the motion of the lever arm G², in accomplishing this locking pressing down the spindle H', through its collar 60

H², and opening the air valve H, so that the bottom of the cylinder D⁹, is in communication with the atmosphere. The exact point to which the piston F³, shall move down is determined by the adjustment of the screw 70 abutment E. The shoulder F⁴, is formed on a nut adjustable on the threaded rod F², and is adjusted to correspond with the position of the abutment E.

When the carrier reaches the end of the 75 tube from which it is to be delivered it strikes against the fluid valve L, raising this valve and through the lug or lugs L⁴, the rod M, is drawn upward until its enlargement M', engages the lever arm G², and acts upon it so as to draw the stop lever G', out of engagement with the shoulder F⁴, whereupon the atmospheric pressure acting on the piston valve F', causes this valve and its connected part F, to move upward to the position shown in Figs. 3 and 4, cutting off the connection between the transit tube and the 80 vacuum pipe.

As shown, I have arranged the valve spindle K, in connection with the collar K², with 85 its finger K³, so that when it is desired to insert a carrier the spindle is turned with the effect of raising the valve L, so as to give access to the end of the transit tube and also of shifting the valve I', to the position 90 shown at the right hand side of Fig. 7.

The mechanism shown is characterized by 95 its simplicity and effectiveness. Aside from the transit tubing running between the two stations, the only connection between the 100 stations is the auxiliary pipe J', which, with the pilot valves I', forms the controlling mechanism for the pneumatically actuated means for obtaining carrier movements in either direction between the stations. The 105 pneumatically actuated means comprising the two vacuum connections C, C and the valve mechanism controlling communication between the vacuum connections C, C and the ends of the transit tubing A form compact and efficient instrumentalities for the 110 purpose for which they are designed and used.

It will be obvious that my device is capable 115 of many variations and modifications without departure from the underlying invention and I wish it to be distinctly understood that save where specific mechanical details are made a part of the combinations claimed I do not wish to be understood as 120 in any way limiting myself to the mere mechanism illustrated.

Having now described my invention, what 125 I claim as new and desire to secure by Letters Patent is—

1. In a pneumatic despatch tube system in which carriers are transmitted in either direction between two stations, transit tubing normally open to the atmosphere through which carriers are transmitted between the 130

stations, pneumatically actuated means for creating a flow of air through the transit tubing to move the carrier from either station to the other, and controlling mechanism therefor, comprising a pilot valve at each station, operated upon the insertion of a carrier at that station, and an auxiliary tube running between the stations to which the pilot valves are connected and which is adapted to have an air flow set up in it when either pilot valve is operated.

2. In a pneumatic despatch tube system in which carriers are transmitted in either direction between two stations, transit tubing normally open to the atmosphere through which carriers are transmitted between the stations, an exhaust chamber, pneumatically actuated valve mechanism for connecting said tubing to said exhaust chamber to create a flow of air through the transit tubing for moving a carrier from either station to the other, and actuating mechanism for said valve mechanism, comprising a pilot valve at each station, operated upon the insertion of a carrier at that station, and an auxiliary tube running between the stations and so connected to said pilot valves and said exhaust chamber that when either pilot valve is operated an air flow is set up through said auxiliary tube which operates said valve mechanism.

3. In a pneumatic despatch tube system the combination with the transit tubing connecting two stations of a valve mechanism at each station for setting up an air flow toward said station from the other station through said transit tubing, and means at each station for operating the said valve mechanism at the other station.

4. In a pneumatic despatch tube system a single line of transit tubing through which carriers are transmitted in either direction between two stations, a valve mechanism at each station for setting up an air flow toward said station from the other station

through said transit tubing and means at each station for operating the said valve mechanism at the other station.

5. In a pneumatic despatch tube system a single line of transit tubing through which carriers are transmitted in either direction between two stations, a valve mechanism at each station for setting up an air flow toward said station from the other station through said transit tubing and means at each station for operating the said valve mechanism at the other station, said mechanism and means at each station being operatively connected to the means and mechanism at the other station by a common auxiliary tube.

6. In a pneumatic despatch tube system, a single line of transit tubing through which carriers are transmitted in either direction between two stations, a pneumatically actuated valve mechanism at each station for setting up an air flow toward said station from the other station through said transit tubing, pneumatic means at each station for operating the said valve mechanism at the other station, and a common auxiliary tube connecting the said mechanism and means at each station to the means and mechanism at the other station.

7. In a pneumatic despatch tube system, the combination with a transit tubing connecting two stations, of a vacuum pipe at each station and a valve mechanism at each station for connecting the corresponding end of the transit tubing to the corresponding vacuum pipe, and means at each station for utilizing the difference between the pressure of the atmosphere and the pressure in the corresponding vacuum pipe to operate the valve mechanism at the other station.
